UNITED STATES PATENT OFFICE.

WALTER O. AMSLER, OF TOLEDO, OHIO, ASSIGNOR TO THE LIBBEY-OWENS SHEET GLASS COMPANY, OF TOLEDO, OHIO, A CORPORATION OF OHIO.

DRAW-TABLE-HEATING UNIT.

Application filed October 9, 1924. Serial No. 742,508.

The present invention relates to a sheet glass drawing apparatus draw-table, and has particular reference to means for controlling the flame used to heat the said draw-table.

5 An important object of the invention is to provide means for controlling the angularity of deflection of the flame used to heat the draw-table in a manner that the draw-table can be heated to any desired temperature and 10 maintained at a constant temperature.

A further object of the invention is to provide novel means for controlling the play of the flame on the edge of the draw-table, the said means being adjustable from the exterior 15 of the machine.

Other objects and advantages of the invention will be apparent during the course of the following description.

In the drawings wherein like numerals are 20 employed to designate like parts throughout the same,

Fig. 1 is a fragmentary longitudinal section showing the device in use,

Fig. 2 is a transverse section thereof, 25 Fig. 3 is a fragmentary sectional view showing various positions of deflecting means, and

Fig. 4 is a rear view of the device positioned on the sheet glass drawing apparatus.

30 In the drawings wherein for the purposes of illustration is shown the preferred embodiment of the invention, the numeral 5 designates a draw-pot containing a source of molten glass 6 from which is drawn a sheet 7 adapted to be bent over a bending roll 8 and passed over a draw-table 9. Arranged above the draw-table 9 is a flattening table 10 operable upon the drums 11. The draw-table 9 comprises a plurality of preferably metallic 35 links 12 forming substantially an endless flexible belt which is supported upon the drums 13, and which is kept taut by means of an idler 14. The draw-table 9 passes over draw-table rails 15 which hold the draw-table in a substantially perfectly flat horizontal plane.

To prevent too rapid cooling of the sheet 7 as it passes over the draw-table it is necessary to heat the various links, and to this end a flame 16 is utilized.

50 The flame 16 which is produced by a suitable source of gas 17 is introduced within the draw chamber through the ports 18. Arranged preferably on the exterior of the machine is a support 19 upon which is pivotally mounted a bracket 20 carrying a slab 21

formed from a refractory material. The bracket 20 terminates in the lip 22 having an opening 23 formed through and adapted to receive a preferably screw-threaded shaft 24. The shaft 24 is carried by the support 19, and 60 in the preferred construction has a thumb nut operable upon the screw-threaded end of the shaft. Upon operation of the thumb nut 25 the bracket can be raised or lowered as shown in Fig. 3, thus controlling the angularity of 65 deflection of the frame with respect to the draw-table 9.

From the foregoing it will be seen that with the use of the adjustable slab 21, which is carried by the pivoted bracket 20, the flame 16 70 can be directly or indirectly applied to the draw-table, thus controlling the temperature thereof to give the best results.

It is to be understood that the form of the invention herewith shown and described is to 75 be taken as the preferred embodiment of the same, and that various changes in the shape, size and arrangement of parts may be resorted to without departing from the spirit of the invention or the scope of the subjoined claims. 80

I claim:

1. In combination with a sheet glass drawing apparatus draw-table, of means to create a flame to heat the draw table, and means to deflect the flame from its normal path to 85 any desired angle with respect to the draw-table.

2. In combination with a sheet glass drawing apparatus draw-table, of means to create a flame to heat the draw table and a slab to 90 deflect the flame to any desired angle with respect to the draw-table.

3. In combination with a sheet glass drawing apparatus draw-table, of means to create a flame to heat the draw table, means arranged in the path of the flame to deflect the same, and means to adjust the said means to control the angularity of the deflection of the flame. 95

4. In combination with a sheet glass drawing apparatus draw-table, of means to create a flame to heat the draw table, a slab arranged in the path of the flame to deflect the same, and means to adjust the slab to control the angularity of deflection of the 100 flame with respect to the draw-table.

5. In combination with a sheet glass drawing apparatus draw-table, of means to create a flame to heat the draw table, a support, a bracket on the support, and a slab carried 110

by the bracket and arranged in the path of the flame to deflect the same toward the draw-table.

6. In combination with a sheet glass drawing apparatus draw-table, of means to heat the same, including means to create a flame, a support, a bracket pivotally mounted on the support, a slab carried by the bracket and arranged in the path of the flame to deflect the same toward the draw-table, and means to adjust the said bracket and slab.

7. In combination with a sheet glass drawing apparatus draw-chamber having ports therein, of a draw-table and means arranged in proximity to the ports to deflect a flame on said draw-table to heat the same.

8. Means for mounting a slab, comprising a bracket, a support, means for pivotally mounting the bracket associated with the

slab on the support, and a screw-threaded shaft operable through the bracket for moving the same together with said slab to adjust the angularity of the latter,

9. The method of heating a draw table in sheet glass apparatus, which consists in deflecting a flame out of its normal path onto the table at the desired angle relative thereto.

10. The method of heating a draw table in sheet glass apparatus, which consists in creating a flame whose normal path is beneath the draw table, and deflecting said flame out of its normal path onto the table at the desired angle relative thereto.

Signed at Toledo, in the county of Lucas, and State of Ohio, this 7th day of October, 1924.

WALTER O. AMSLER.
